UNITED STATES PATENT OFFICE.

EDWIN S. WHITE AND ALBERT W. KELIN, OF PITTSBURGH, PENNSYLVANIA.

BOTTLE-OPENER.

1,366,045.

Specification of Letters Patent. Patented Jan. 18, 1921.

Application filed May 24, 1920. Serial No. 383,806.

To all whom it may concern:

Be it known that we, EDWIN S. WHITE and ALBERT W. KELIN, citizens of the United States, residing at Pittsburgh, in the 5 county of Allegheny and State of Pennsylvania, have invented certain new and useful Improvements in Bottle-Openers, of which the following is a specification, reference being had to the accompanying drawings.

This invention relates to bottle openers and more particularly to a bottle opener for removing disk stoppers.

An object of the invention, is to provide 15 an opener of this character capable of removing a disk stopper regardless of how firmly the stopper may be positioned in the bottle.

Another object is to provide an opener of 20 this character including a plate to which a lever is pivoted, the lever being arranged to penetrate the stopper and urge the plate toward the stopper.

Another object is to provide an opener 25 of this character including a plate having a pair of aligned slots, the portion of the plate extending between said slots serving as a fulcrum for the lever of the opener.

A still further object of the invention, is 30 to provide a bottle opener of this character including a hook, which is forced downwardly toward one portion of the disk stopper and up through an adjacent portion, so as to prevent accidental disengagement 35 of the stopper from the opener when the stopper is being removed.

With these and other object in view, the invention consists in the improved construction and arrangement of parts to be hereininafter more particularly described, fully 40 claimed and illustrated in the accompanying drawings, in which:

Figure 1 is an elevation partly in section showing the position of the opener 45 when the hook thereof is entering the disk stopper.

Fig. 2 is an elevation partly in section showing the lever and hook of the opener in the position previous to removing the disk 50 stopper, and

Fig. 3 is a top plan view with the lever of the opener in the position shown in Fig. 2. Referring to the drawings, 5 designates a plate of a size sufficient to engage a disk 55 stopper, such as the stopper A used in connection with milk bottles. The plate 5 has

its intermediate portion extended upwardly, so that the central portion is substantially concavo convex. Slots 6 and 7 are formed in the plate 5, in alinement with each other, 60 a fulcrum 8 being formed by the portion of the plate between the slots, the purpose of which will be hereinafter described.

In connection with the plate 5, a lever 9 is used. This lever is formed from a single length of material having its end portion curled upon said length to provide a finger piece. The end portion 11 is extended back upon the length to provide a bearing 12 and then extended back upon 70 itself and curved to provide a hook 13. It will be noted that the bill of the hook is disposed in spaced relation to the bearing 12 and projects beyond the side of said lever. The lever 9 is intended to be pivoted 75 to the plate, by inserting the fulcrum 8 between the end portion 11 and body portion of the lever into the bearing 12. The last mentioned portions, are then moved toward each other to prevent disengagement of the 80 lever. By this arrangement, the hook 13 is caused to swing downwardly through the slot 6 and upwardly through the slots 7.

In the use of the device, the plate 5 is disposed in engagement with the disk stopper, and the lever moved toward the slot 6 so as to cause the hook 13 to pass through the slot 6 and penetrate the stopper. The movement of the lever toward the slot 6 is continued so as to cause the hook 13 to penetrate the lower surface of the stopper in spaced relation to the first opening formed in the stopper. The hook is then moved upwardly through the slot 7 and thereby engages the stopper at two points and forces 90 the plate 5 into firm engagement therewith. The stopper may then be readily removed without danger of the same tearing or the lever disengaging itself from the stopper. It also holds the stopper so that it may be 100 applied and removed as often as necessary without disengaging the opener from the stopper and in this manner, it serves as a handle.

An important feature of this opener, is 105 that by providing the concavo convex central portion in the plate 5, the bearing 12 is disposed within the concave portion so that when the plate is moved toward the stopper there are no projections to interfere with 110 the engagement of the plate with the stopper and at the same time a fulcrum is pro-

vided by utilizing a portion of the plate. It will also be noted that the hook 13 penetrates the stopper at two points that is, it goes in at one point and comes out at another so 5 that if the stopper is firmly positioned within the bottle it is impossible for the same to be torn and only partially removed as the stopper is curved firmly to the metal plate by means of the hook which overcomes a 10 tendency of the stopper to resist extraction.

From the foregoing it will be readily seen that this invention provides a novel bottle opener capable of removing any form of disk stopper, and one which is composed 15 of only two pieces of metal namely the plate and the lever, which are so constructed that no additional pivot or fastening means are necessary, and these parts can be stamped from sheet metal.

20 What we claim is:—

As an article of manufacture, a bottle opener comprising a plate, the marginal

edges of said plate being arranged for engagement with the disk closure of a bottle, the intermediate portion of said plate 25 being raised above the plane of the marginal edges to provide a fulcrum, said plate having a pair of longitudinally aligned slots penetrating a portion of the marginal edges and the fulcrum, the portion of said fulcrum disposed between the slot providing a shaft, and a lever having one end portion extended back upon itself to provide a finger piece, the other end portion of said lever being extended back upon the lever in 30 alignment with the finger piece to provide a hook, the bight portion of the last mentioned end portion being enlarged and adapted to loosely embrace the shaft.

In testimony whereof we hereunto affix 40 our signatures.

EDWIN S. WHITE.
ALBERT W. KELIN.
